JULIUS CLOSSMANN AND HEINRICH HALBERSTADT, OF VIENNA, AUSTRIA.

ARC-PREVENTING DEVICE.

Application filed December 16, 1922. Serial No. 807,441.

To all whom it may concern:

Be it known that we, JULIUS CLOSSMANN, engineer, and HEINRICH HALBERSTADT, engineer, both citizens of the Republic of Austria, residing at Vienna, in the Republic of Austria, have invented certain new and useful Improvements in Arc-Preventing Devices, of which the following is a specification.

10 It is known that in electric switches, more especially those for heavy currents, the arcing or sparking when the circuit is broken rapidly renders the contacts useless. Consequently many devices for extinguishing arcs or sparks have been suggested, which, however, by reason of the expensive and complicated auxiliary apparatus required are only employed in cases where very exceptional dangers or disadvantages result 20 from the arcing or sparking.

The subject of the invention is a switch device wherein by the shape of the contacts and also their arrangement and movement, the occurrence of arcing at the original contact places is rendered quite impossible, and any arcs that may be formed at other places are efficiently suppressed. This result is obtained according to the invention without any auxiliary apparatus by suitably shaping the contacts and by the connection of one contact with the other; additional advantages result from the relation of the arm to the movable contact and by its movement.

25 Hereinafter we particularize in the description of embodiments of our invention, show embodiments in the accompanying drawings, and finally point out the invention in the appended claims.

30 The invention is diagrammatically illustrated in the accompanying drawings, in which:

Fig. 1 is an elevation of the contacts of the present invention, the dotted line position of the movable contact being the normal circuiting position, and the full line position of such movable contact being the final contact position as the movable contact moves to open circuiting relation;

35 Fig. 2 is a side view of the same, the movable contact being shown in closed circuiting position in full lines, and additionally shown in position as it opens, and in full open circuit position in dotted lines;

40 Fig. 3 is a similar side view, showing circuit closed position in full lines and circuit

open position in dotted lines, with a different form of movable contact;

45 Fig. 4 is a side view showing a slightly modified form of contacts;

Fig. 5 is an elevation of Fig. 4, showing 50 additionally the position of the movable contact in its final contact position;

Fig. 6 is an elevation partly in section of a further embodiment of the invention, the 55 form of the contacts being modified;

Fig. 7 is a diagrammatic view illustrating the arc formation and showing in dotted lines the magnetic field about the arm of the movable contact;

Fig. 8 is a side view of a structure embodying the invention of the foregoing 60 views;

Fig. 9 is a plan view of the same; and

Fig. 10 is a view taken from line 10—10 65 of Fig. 8.

Similar characters of reference indicate corresponding parts throughout the several views.

With more particular reference to Figs. 1 and 2, the movable contact *a* is here shown in the form of a figure of revolution, though obviously it may be of any other form, the width of which alters in the plane of the contact surface or perpendicularly to such surface. The fixed contact here indicated 70 at *b*, is longitudinally divided with the arms thus formed slightly flattened in the direction of motion, as indicated at *c*, Fig. 2, with the proximate edges of said arms divergent, as indicated at *d*, Fig. 1. The movable contact *a*, is carried by an arm *m*, operating 75 relative to a remote center, though other methods of support and operation of the movable contact can be readily utilized. In the normal circuiting relation between the 80 movable contact *a* and the fixed contact arms *b*, as indicated by dotted lines in Fig. 1, and full lines in Fig. 2, it will be noted that the contact area between these contacts is a comparatively small area where the substantially rounded or conical operative surface of the movable contact co-operates with the immediately underlying portions of the contact arms *b*.

85 As the movable contact *a* moves to open circuiting position, it will be 85 apparent that the line of contact between the respective contact members is directed angularly of the arms *b*, due to the divergent edges *d* and laterally or radially of the contact *a*, due to the surface of such contact and 90

95

100

105

110

- to the divergence of the edges of the arms *b*. Thus without interrupting the electrical engagement between the contacts, it will be apparent that the normal contact area, when 5 the contacts are in circuiting position, is entirely distinct and widely separated from the contact area of such contacts at the moment the electrical engagement between the contacts is broken. If arcing results in the 10 separation of the contacts, it will be apparent that this arcing occurs at points on said contacts which are widely separated from the normal contact area of such contacts. Thus the arcing, no matter how pronounced, 15 will be without effect of any kind upon the normal contact area of the contacts, and hence such normal contact area will remain at all times in the best possible condition for electrical circuiting.
- 20 The movable contact can also be formed, for example by a roller *a*, (Figures 4 and 5), or of a spherical surface or of a cone, or in the form of a disc of rhomboidal form or any other body having a varying breadth.
- 25 The securing of the movable contact in the contact position can take place for example by spring pressure which can be effected quite easily when the fixed contact has an inclined or ramped surface *c*² (as shown in 30 Fig. 2). This ramped surface, when the current is flowing, bearing against the contact *a*, due to the spring produces a sufficient amount of friction or pressure to hold the movable contact firmly in "circuit 35 closed" position.
- A recess *h* shown in Figs. 2, 4 and 5 of corresponding form to the movable contact serves as a rest surface for the movable contact to increase the security against unintentional movement of the lever.
- 40 Instead of the securing devices just described, there can be used the spring clip or tongue *k*, shown in Fig. 6, from which the movable contact arm *m* can only be removed 45 when the extensions *i* are pressed together.
- In cases where, as in Figs. 1, 2, and 3, the movable contact arm *m* passes between the fixed contacts *b*, in order to prevent arcing or sparking between the parts at these places, 50 the fixed contacts can be provided between the arm *m* and the side surface of the fixed contacts *b*, *b*, with plates of insulating material, as indicated at 1 in Fig. 1.
- 55 In Figs. 8, 9, and 10, a structure is shown which embodies the invention herein described. A slate base *n* has a conductor *o* with thumbscrew *o'* thereon, which conductor connects electrically with one end of one or more convolutions *q* and the member *m*, which has the contact *a*. Another conductor *r* with thumbscrew *r'* electrically connects with contact *b*.
- 60 The convolution or convolutions surround a core *s*, and the arm *m* is limited in its movement by the shoulder *t*.

The extinction of the arcs or sparks at the edge of the movable contact or roller, etc., occurring during the drawing away of the movable contact from the other contact is effected by suitably forming the movable contact arm *m* substantially perpendicular to the direction of motion of the movable contact, and subjecting the arm to the action of a powerful spring or other means capable of imparting to it a rapid movement. This condition is also approximately fulfilled by a circular movement of the current arm, as shown in Figs. 2 and 7. The extinction of the arcs or sparks in this case takes place by the blowing out of any arc 75 that may form, and furthermore a back electromotive force is produced, which prevents the occurrence of an arc.

Fig. 7 shows diagrammatically the most favorable conditions in this respect. Around the movable conductor *m* as well as around the arc *e* as a second conductor, there are lines of force which repel each other and thus extinguish the arc. Above all, the lines of force *f* which are produced around the movable conductor *m* and which in the movement of the conductor *m*, cut those of the arc produced, generate a back electromotive force in a direction contrary to the arrows *g* and *p* which increases with the rate at which the lever arm moves. This electromotive force acts in the opposite direction to the current indicated by *g* and *p* flowing in the arcs or sparks, and consequently effects the instantaneous extinction 100 of the latter.

When the switch is closed with the contact *a*, in effective contactual relation to the contact *b*, and a normal or less than normal current flows therethrough, the current sets up fields of force, as is well known, around the contact *a*, contact *b*, and arm *m*. On the separation of the contact *a*, from contact *b*, as in Fig. 4, an arc is produced, and this sets up in the known manner its field of force. The movement of the arm *m*, cuts the lines of force surrounding the arc. At the same time the arc shifting its position cuts the lines of force of conductor *m*. These relations, of course, change rapidly, and cannot be shown in the drawings with definiteness, though they are indicated in Fig. 4, and will be clear to anyone skilled in the art. Increase of current increases the lines of force. When, then, a current larger than the normally intended or excess current flows through the parts, on the breaking of the circuit, then the fields of force will be correspondingly increased. The field around the arm *m* will act to blow on the arc, as certain of the lines of force repel each other, under Ampère's law of parallel and oblique circuits; or the arc will move away from the field of force of arm *m*, as it also always de- 110 115 120 125 130

sires to place itself into the path of least resistance. This movement of the arc and attenuation causes a cutting of lines of force. By the co-operation of the parts, a counter or opposing electromotive force is set up. The speed of movement of the parts increases the same. This counter electromotive force acts as stated to extinguish the arc. When the arc is split into two parts 10 as when two contact members *b*, are used, the extinguishment is quicker.

It will have been seen that the contact *a*, has an effective contact surface with contact *b*, under normal conditions. When 15 the contact *a*, is moved along contact *b*, the contactual surface is decreased and gradually changed. But as the parts separate, the last contactual relationship is at a portion of the contact *b*, distant as far 20 as possible from its initial effective contact surface, and is at a portion of contact *a*, distant as far as possible from its initial effective contact surface, namely at its perimeter in Figs. 1 and 2. No arcing 25 takes place at the initial contactual surfaces, but at a distance therefrom. Any arcing produced does not burn or fuse the effective contact surfaces.

It is obvious that the above arrangement 30 is entirely independent of the direction of the current, and that the effects sought are obtained quite consistently with either direction of the current.

It is of course apparent that the switch 35 construction described is equally effective whether the movable contact *a*, is a circuiting member or whether it is merely a bridge member between the two independent circuiting members which would under 40 such circumstances be the separate arms *b*.

While we have herein shown and described several practical embodiments of the invention, it is understood that changes 45 may be made therein without departing from the spirit and scope of the invention as claimed.

What we claim is:

1. An arc preventing device, comprising 50 cooperating switch members, each having on the switch member itself a normal contact area forming the sole electrical connection when the members are in circuiting position, and each having a contact area on the switch member itself independent from said normal contact area and serving as the sole electrical connection as the members approach an open circuiting relation.

2. An arc preventing device, comprising 55 cooperating switch members having relative movement in contact from a normal closed circuit relation to an open circuiting relation, the electrical contact area between the switch members themselves in normal closed circuit relation being spaced 60 from the contact area between the members

themselves as said members approach an open circuiting relation.

3. An arc preventing device, comprising 65 cooperating switch members having relative movement in contact from a normal closed circuiting relation toward an open circuiting relation, said members themselves being relatively formed to any possible tendency in the separation of the members between 70 points wholly free of contact when the members are in normal closed circuiting relation.

4. An arc preventing device comprising 75 two contacting members, one movable with respect to the other to open or close the circuit, the members being so relatively formed as to wholly change the point of contact between the members themselves with respect to each other from their positions in circuiting relation to their positions at the instant of breaking the circuit. 80

5. An arc preventing device comprising 85 two contracting members, one movable with respect to the other to open or close the circuit, the members being so relatively formed as to maintain a definite contact area between the members themselves in circuit closed position and compel a wholly independent relative contact area between the members themselves at the instant of opening 90 the circuit, and means to operate one member with respect to the other to insure such contact variation. 95

6. An arc preventing device comprising 100 contact members adapted for relative movement, one of said members having a contact portion inclined with respect to the path of movement of the contact portion of the other member, whereby the contact surfaces of the members themselves vary in position during 105 the movement of the members relative to each other.

7. An arc preventing device comprising 110 contact members adapted for relative movement, one of said contact members having spaced inclined contact portions and the other of said members having a rounded contact portion, and means operating between the inclined contact portions of the first member to move the other of said members, whereby to constantly change the contact area between the members themselves 115 during their relative movement.

8. An arc preventing device comprising 120 relatively movable contact members, one of said members having a contact portion inclined with respect to the other contact member, said other contact member being formed of a body of revolution adapted for movement lengthwise the inclined contact portion of the other member, whereby in opening the circuit the contact areas between the members themselves are constantly changed. 125

9. An arc preventing device comprising 130 relatively movable contact members, one of

said members having a contact portion inclined to the path of movement of the other of said members, said other member having a curved contact space to engage the first member, whereby in the open circuiting movement of the members the electrical contact between the members themselves is directed at an angle to the path of movement of the operated member.

10 10. An arc preventing device comprising contact members, one movable with respect to the other, one of said contact members having spaced inclined contact portions and the other of said member having a curved contact space bridging the space between the inclined contact portions of the first member, and means for operating said other member to cause the line of contact to move on divergent lines at an angle to the path of movement of such other member during the open circuiting movement of the members.

11. An arc preventing device comprising relatively movable contact members, one of said members having spaced divergent contact portions laterally inclined with respect to the path of movement of the other member, such other member having a contact surface bridging the space between the contact portions of the first member, and means to operate such other member along and away from the first member, whereby the contactual surfaces become less until separation takes place.

12. An arc preventing device comprising relatively movable contact members, one of said members having longitudinally disposed spaced contact surfaces having terminal relatively divergent portions, the other of said contact members having a curved face bridging the spaced contact surfaces of the first member to maintain contact while providing portions of each contact member normally out of electrical engagement, and means for operating such curved contact member to utilize normally free contact portions of both members as the final contact area.

13. An arc preventing device comprising relatively movable contact members, having their surfaces relatively formed to constantly change the contact area between the members themselves as said members move to open the circuit, and a rod connected to and operating one of said contact members, said rod being arranged at right angles to its connected member.

14. An arc preventing device for preventing or extinguishing arcs or sparks at the contacts of electric switches, characterized in that one or both of the contacts has or have an extension of breadth, a contraction, a flattening or a curvature, which varies in amount and which during the sliding of the contacts on each other produced by the movement of the switch, effects a continual

change in the places of engagement of the contacts themselves so that the separation of the contacts themselves finally takes place at places which lie at a distance from the original two places of contact.

15. An arc preventing device, comprising a contact, a second contact, said contacts being movable one in respect to the other, said contacts having means decreasingly varying the contactual surfaces of the said contacts, from full effective contact up to no contact on the point of separation of the contacts under maintenance of electrical engagement between the contacts, and an arm for said movable contact arranged perpendicular to the direction of motion for each position of the movable contact, and capable of a very rapid motion from closed circuit position to open circuit position.

16. An arc preventing device, comprising a contact, a second contact, one movable in respect to the other, said contacts having means decreasingly varying the contactual surfaces of the said contacts, from full effective contact up to no contact on the point of separation of the contacts under maintenance of electrical engagement between the contacts, an arm for said movable contact arranged perpendicular to the direction of motion for each position of the movable contact and capable of rapid motion from closed circuit position to open circuit position, and means holding the contacts in closed circuit position.

17. An arc preventing device, comprising a movable contact, a second contact having an inclined cut away portion oblique to the path of movement of the movable contact for decreasing the contactual surfaces as the movable contact moves over the second contact until separation takes place, and means elastically pressing said contacts together on normal current flow, and separating the contacts and giving the movable contact a rapid motion away from the second contact.

18. An arc preventing device, comprising a contact, substantially circularly movable in respect to a pivotal point, a second contact having an effective contact surface, and a curved portion curved in line with the path of motion of the movable contact, and having an inclined portion oblique to the direction of motion of the movable contact, whereby the varying contactual surfaces change in two directions at right angles to each other on the movement of the movable contact over the second contact, and means on the movable contact pressing said contacts together on normal current flow, and separating the contacts and giving the movable contact a rapid motion away from the second contact.

19. An arc preventing device, comprising a circular contact, a second contact having

an effective contact surface, and a portion curved away from the effective contact surface, and having a cut out forming a slot in the divergent walls, means movable in the slot and on the circular contact pressing the circular contact against the effective contact surface on normal current flow, and moving the circular contact bridge fashion on the divergent walls and separating the contacts from each other.

20. An arc preventing device, comprising a pivoted conductor, movable in a plane, a contact at right angles thereto at its free end, and movable therewith, and a second contact having a surface in a plane perpendicular to the plane in which the conductor moves and having a portion curved to substantially conform to the path of movement of the first contact, the edge of the curved portion being closer to the edge of the first contact than any other portions of the contacts, whereby any arc formed between edges is extinguished in the movement of disengagement of the contacts, by the field pro-

duced by the current passing through the conductor and the counter electromotive force created.

21. An arc preventing device, comprising an electrical contact, having an effective contact surface, a second contact having an effective contact surface, all electrical contact between the said contacts being made by the contacts themselves, the said contacts when contacting in closed circuit position having their effective contacting surfaces in a common plane, and a member for one of said contacts movable in a plane perpendicular to the common plane of the contacts, said contact supporting member not contacting with the other contact.

In testimony whereof we have hereunto set our hands.
